(57) CLAIM

The ornamental design for a shirt, as shown and described.

DESCRIPTION

FIG. 1: is a front elevational view of a shirt, showing our new design; and,

FIG. 2: is a front elevational view thereof, showing the front opening at an enlarged scale.

The dot-dot-dash lines shown in the drawings are for illustrative purposes only and form no part of the claimed design.
